CLAIM

The ornamental design for a shoe, as shown and described.

DESCRIPTION

The file of this patent contains at least one drawing/photograph executed in color. Copies of this patent with color drawing(s)/photographs(s) will be provided by the Office upon request and payment of necessary fee.

FIG. 1 is a top, left, front perspective view of an ornamental design for a shoe that has surface indicia on the front sole; FIG. 2 is a left side elevational view of the shoe of FIG. 1; and,

FIG. 3 is a right side elevational view of the shoe of FIG. 1. The dash-dash-dash broken lines are included for the purpose of illustrating portions of the shoe that form no part of the claimed design. A transition in color including the colors of orange and yellow is shown.

1 Claim, 3 Drawing Sheets
